ELECTRIC LAMP AND MOUNTING

Frank E. Carlson, East Cleveland, Ohio, assignor
to General Electric Company, a corporation of
New York

Application May 17, 1941, Serial No. 393,924

7 Claims. (Cl. 176—32)

My invention relates in general to bases and mountings for electric lamps, and is particularly applicable to prefocused electric lamps which are adapted to be inserted, bulb first, into the lamp socket or mounting.

In certain types of motion picture projectors in use at present, the electric incandescent lamp constituting the light source for the projector is assembled in place within the projector lamp housing by inserting the lamp, bulb first, through an opening in the bottom of the housing, the lamp being held in place in the housing by means of a bottom closure cap threaded into the said opening at the bottom of the housing. To position the lamp in a predetermined position within the lamp housing, a prefocusing arrangement is employed which comprises an inwardly projecting positioning ring or collar within the lamp housing having a slot therein, and a laterally extending flange on the lamp base adapted to engage the under surface of the collar and provided with an upwardly extending lug adapted to enter the slot in the collar so as to position the lamp in a predetermined position angularly of its axis. With such an arrangement, it is unnecessary to have access into the bulb chamber of the lamp housing for lamp installation or removal purposes; and it is not necessary to grasp the body of the lamp in the installation or removal of the lamp.

Heretofore, the assembly of the electric lamp in such projector lamp housings has been more or less difficult and inconvenient because of the necessity for manually holding the lamp up within the lamp housing with the upwardly extending positioning lug on the lamp base engaged within the slot in the positioning collar, and then quickly retracting the hand and immediately positioning the bottom closure cap underneath the lamp before the lamp can drop out of the housing or drop to the point where the upstanding lug on the lamp base is withdrawn from the slot in the positioning collar.

One object of my invention is to provide an electric lamp and socket arrangement which facilitates the installation and removal of the lamp through the bottom of the socket and which provides an accurate positioning of the lamp within the socket.

Another object of my invention is to provide, in an electric lamp and socket arrangement permitting installation and removal of the lamp through the bottom of the socket, preliminary support means for temporarily supporting the lamp within the socket prior to the application of

the final lamp support means to the lamp socket.

A feature of the invention is the provision of lug means on the lamp base which is adapted to enter a slot in a lamp positioning collar disposed within the lamp socket and which is further adapted to engage and rest on the top surface of the said lamp positioning collar to thereby support the lamp in, and prevent the same from dropping out of the socket.

Further objects and advantages of my invention will appear from the following description of species thereof and from the accompanying drawing, in which:

Fig. 1 is a vertical section of the lamp housing of a motion picture projector equipped with a lamp and socket according to my invention; Fig. 2 is a fragmentary view, partly in section, of the lamp and socket shown in Fig. 1 with the lamp shown at an intermediate stage of its assembly within the socket; Fig. 3 is a perspective view of the prefocusing lamp collar with which the lamp shown in Figs. 1 and 2 is provided; Figs. 4 and 5 are perspective views of two modified forms of prefocusing collars comprising my invention; and Fig. 6 is an end view of the base end of the lamp shown in Figs. 1 and 2.

Referring to the drawing, an electric incandescent lamp 10 is shown mounted in place within a vertical cylindrical lamp housing or casing

30 11 comprising a metallic upper main portion 12 and a lower socket portion 13 consisting of a body of suitable molded insulating material secured to the bottom of the main casing portion 12 in any suitable manner, such as by screws 28.

35 The insulating body or socket portion 13 has a relatively large vertical bore 14 therethrough communicating with the hollow interior of the upper main lamp housing 12. Molded in the socket body 13 coaxial with the bore 14 therein and intermediate the top and bottom of the body is a metallic positioning collar or ring 15 which projects inwardly from the surface of the bore 14 and forms a downwardly facing annular contact and positioning surface 16. Likewise molded

40 in the socket body 13 coaxial with the bore 14 therein, and disposed below the ring 15 and insulated therefrom, is a cylindrical internally screw-threaded metallic conductor member or sleeve 17. Removably secured to the bottom of the socket body 13 so as to close off the bottom of the bore 14 is a closure cap 18 comprising an upwardly facing cup-shaped metallic member 19, externally screw-threaded for threaded engagement with the conductor member 17, and a cover member 20 of suitable insulating material se-

45

cured to the exterior surface of the metal cup member 19 and provided with a hand knob 21 for convenient insertion and removal of the closure cap. Secured to the upper surface of the metal cup member 19 is a spring contact blade 22 the free end of which is disposed centrally of the member 19 so as to engage the bottom end contact 23 of the lamp 10.

The ring 15 and the sleeve member 17 are provided with lateral extensions or lugs 24 which extend through the wall of the socket body 13 to externally exposed points within recesses 25 formed in the body. The said extensions or lugs 24 form the terminals of the lamp socket to which are attached wires 26, from a source of current, by conventional headed screws 27 screw-threaded into the lugs 24.

The bore 14 in the socket body 13 and the coaxial openings in the ring 15 and sleeve member 17 are formed of sufficient size to permit the bulb 29 of the electric incandescent lamp 10 to be passed upwardly through the socket bore 14 and the said openings in the ring and sleeve members 15 and 17 into the position shown in Fig. 1 wherein the bulb 29 is disposed within the main lamp housing 12. The lamp 10 comprises, in addition to the bulb 29, a concentrated filament 30 mounted with the bulb and a conventional lamp base 31 secured to the lower end of the bulb and comprising a cylindrical metallic shell portion 32 and the aforementioned bottom end contact 23 separated by suitable insulation 33. Fitted over the shell 32 of the lamp base and secured thereto in any suitable manner, such as by soldering, is a metallic prefocusing contact collar or adapter 34 comprising laterally projecting flange means preferably in the form of a circumferential flange 35 disposed substantially normal to the axis of the lamp, and a sleeve or band portion 36 extending upwardly from the inner edge or periphery of the flange 35. The said flange extends laterally beyond the side wall of the lamp bulb 29 and is provided with a flat upwardly facing contact surface 37 which engages the downwardly facing flat contact surface 16 of the ring 15 when the lamp 10 is properly mounted within the socket. Obviously, the laterally projecting flange means 35 need not be formed as a continuous circumferential flange but may be divided instead into a plurality of laterally extending lugs or wings, preferably three or more in number. In addition, the socket ring engaging portions of the flange may be formed of three or more raised protuberances or bosses defining a plane, instead of a flat upwardly facing surface. The sleeve or band 36 of the adapter may, of course, be omitted and the flange 35 used alone as a flat ring, or the said flange may be incorporated in the base shell 32 itself.

When the lamp 10 is inserted in the lamp housing 11 and the bottom closure cap 18 is threaded into place in the socket body 13, the spring contact 22 engages the bottom end contact 23 of the lamp base and forces the lamp up so that the upper surface 37 of the flange 35 is firmly pressed against the under surface 16 of the ring 15. The prefocusing collar 34 is secured to the lamp base 31 with the plane of the upper surface 37 of the flange 35 located in a predetermined position longitudinally and transversely with respect to the lamp filament 30 so that when the lamp is mounted in place within the socket, with the upper surface 37 of the flange 35 in engagement with the under surface of the ring 15, the filament 30 will be located in a predetermined

position within the lamp chamber 11 whereby it is positioned in proper alignment with the optical system of the projector.

The filament 30 of the lamp is of the planar type, such as the conventional monoplane or bi-plane type used in projection lamps. The filament shown in the drawing, however, is of the monoplane type. To position the planar filament 30 of the lamp in a predetermined position angularly of the lamp axis, the prefocusing collar or adapter 34 is provided with a positioning lug 38 extending laterally outward from the sleeve portion 36 of the collar closely adjacent the flange 35 and adapted to enter a slot 39 in the positioning ring 15 and engage one of the side walls 40 (Fig. 2) of such slot, i. e., that wall towards which the lug is apt to be moved by the rotational movement imparted to the lamp by the turning action of the closure cap 18 as it is threaded into place within the socket body 13. The positioning lug 38 is preferably punched or cut out of the sleeve portion 36 of the prefocusing collar; but it may be formed instead of a separate member which is secured either to the said sleeve portion 36 or the positioning flange 37 of the prefocusing collar.

Heretofore, in assembling lamps of the above described construction in the socket 13, it has been necessary to manually support the lamp up within the lamp chamber with the positioning lug 38 disposed within the slot 39 in the positioning ring 15, and then to quickly withdraw the manual support of the lamp and position the bottom closure cap underneath the lamp before the lamp could drop out of the socket or drop down a sufficient distance to allow the positioning lug 38 to become disengaged from the slot 39. Such an operation is more or less inconvenient and is apt to result in the accidental dropping out and breakage of the lamp.

In accordance with the invention, I have provided preliminary or temporary supporting means for the lamp which functions to facilitate assembly of the lamp within the socket by positively supporting the lamp up within the lamp chamber so as to prevent the accidental dropping out of the lamp during the installation or removal of the same. The said temporary supporting means comprises a horizontally extending projection or lip 41 formed at the upper edge of the positioning lug 38 and extending therefrom in a direction tangential to the cylindrical sleeve portion 36 of the prefocusing collar 34. The said projection 41 provides a downwardly facing engagement surface which is adapted to rest on the upper surface of the positioning ring 15 to thereby temporarily support the lamp within the socket whenever the bottom closure cap 18 is not in place in the socket body 13. The overall circumferential width of the positioning lug 38 and its projecting lip 41 is made slightly less than the width of the ring slot 39 so that the lug, with its projecting lip 41, can freely pass through the said slot. The projecting lip 41 preferably extends from that side of the lug 38 which is to engage the shoulder or wall 40 in the positioning ring 15.

In installing the lamp 10, it is first rotated until the positioning lug 38 and its right-angled projection 41 come into alignment with the slot 39 in the ring 15. The lamp is then pushed upwardly until the projection 41 clears the upper surface of the positioning ring 15 after which the lamp is rotated in the proper direction until the vertical abutment surface of the positioning lug

38 abuts against the shoulder 40 in the positioning ring, thus causing the projection 41 to overlie the positioning ring. The lamp is then allowed to drop down until the projection 41 rests on the positioning ring 15, the projection 41 thus serving as a retaining ledge for temporarily supporting the lamp within the lamp housing 11. With the lamp thus temporarily supported within the lamp housing, the bottom closure cap 18 can then be conveniently threaded into place in the socket body 13, the spring contact 22 of the closure cap forcing the lamp upwardly until the upper surface 31 of the positioning flange 35 on the lamp base engages the under surface 16 of the positioning ring 15. The lamp is then in proper assembled position within the lamp housing 11 with the filament 30 in a predetermined position therein. The positioning lug 38 and its right-angled projection 41 thus serve as engagement means for temporarily supporting the lamp within the socket as well as for positioning the lamp in a definite angular position therein.

In the modification shown in Fig. 4, the pre-focusing collar 34 is provided with a pair of lugs 42, 43 extending laterally outward from the sleeve portion 36 of the collar and circumferentially spaced thereon, the said spacing of the lugs, however, being somewhat less than the width of the slot 39 in the positioning ring so that both the lugs can freely pass through the slot at the same time. The lugs 42, 43 are also vertically spaced, i. e., they are spaced axially of the sleeve portion 36. The lower lug 42 serves as the angular positioning means for the lamp while the upper lug 43 serves as the temporary support means for the lamp. The arrangement of the two lugs 42, 43 is preferably such that when the lower lug 42 is in engagement with the shoulder 40 in the positioning ring 15 to thereby angularly position the lamp about its axis, the upper lug 43 will overlie the ring 15 rather than the slot 39. In this manner, the upper lug 43 will engage the ring 15 and support the lamp within the housing 11 when the bottom closure cap 18 is unthreaded from the socket body 13. The two lugs 42, 43 are preferably formed out of the material of the sleeve portion 36 of the prefocusing collar; but if desired, they may be formed as separate members suitably secured to the collar.

In the modification shown in Fig. 5, the positioning flange 35 of the prefocusing collar 34 is provided, at its periphery, with an upstanding lug 44 having a notch 45 formed in one of its radial sides at the lower end thereof and providing a retaining ledge or shoulder 46. The notch 45 extends upwardly from the upper surface 31 of the positioning flange 35 and is of sufficient vertical extent to permit the entry thereinto of the shoulder 40 in the positioning ring 15. The notch is preferably formed in that side of the lug 44 which is moved towards the shoulder 40 in the positioning ring 15 as the bottom closure cap 18 is threaded into the socket body 13. The retaining shoulder 46 formed by the notch 45 serves as the preliminary support means for the lamp, the said shoulder resting on the upper surface of the positioning ring 15 and so supporting the lamp within the housing 11 while the bottom closure cap 18 is screwed into place in the socket body.

Inasmuch as the clearance between the socket and the lamp base is usually insufficient, in those commercial projectors employing the above described lamp mounting arrangement, to permit insertion of an operator's fingers therebetween to 75

enable the grasping of the cylindrical side of the lamp base shell for lamp removal purposes, I prefer to provide suitable finger grip means on the lamp base preferably in the form of lateral lugs or extensions 47 on the base eyelet 48 of the lamp, as shown in Fig. 6. Such lugs or wings 47 provide a ready finger grip on the lamp base and thus facilitate the removal of the lamp from the socket. Alternatively, the finger grip means on the lamp base may be constituted by suitable extrusions punched in or otherwise formed on the lower end of the base shell 32.

What I claim as new and desire to secure by Letters Patent of the United States is:

1. An electric lamp comprising a bulb, a light source within said bulb, and a base secured to said bulb and having laterally projecting flange means for engagement with the bottom surface of a cooperating slotted ring in a socket, said base having engagement means at the upper side of said flange means with a portion arranged to pass through the slotted portion of said ring and engage the upper surface thereof to temporarily support the lamp in the socket, and with another portion arranged to engage a side of the slot in the ring for positioning the lamp in a definite angular position within the socket.
2. An electric lamp comprising a bulb, a light source within said bulb, and a base secured to said bulb and having laterally projecting flange means for engagement with the bottom surface of a cooperating slotted ring in a socket, said base having lug means at the upper side of said flange arranged to pass through the slotted portion of said socket ring and providing a vertical abutment surface for angularly positioning the lamp within the socket by engagement with the side of the slot in the ring, and a downwardly facing engagement surface for temporarily supporting the lamp within the socket by engagement with the upper surface of said ring.
3. An electric lamp comprising a bulb, a light source within said bulb, a base secured to said bulb, a prefocusing collar secured to said base and comprising laterally projecting flange means provided at its inner edge with an upstanding sleeve portion, and lug means extending laterally outwards from said sleeve portion and disposed above said flange means, said lug means having a portion providing a vertical abutment surface for angularly positioning the lamp within the socket and another portion providing a downwardly facing engagement surface for temporarily supporting the lamp within the socket.
4. In combination, an electric lamp socket comprising a tubular body portion and a positioning ring mounted therein transversely of the axis of said tubular body portion, said ring having a slot in its inner periphery extending parallel to the axis of said ring from one side of said ring to the other side thereof, and an electric lamp for insertion into said socket and comprising a bulb, a light source within said bulb, and a base secured to said bulb and adapted to be inserted into said positioning ring, said base having laterally projecting flange means for engagement with said positioning ring, and engagement means on said base adapted to pass through the said slot in said ring and having a portion arranged to engage the upper surface of said ring to thereby temporarily support the lamp within the socket and another portion arranged to engage a side wall of said slot to thereby position the lamp angularly of its axis within the socket.
5. A prefocusing collar for attachment to the

base of an electric lamp comprising a flat positioning flange provided at its inner periphery with an upstanding sleeve portion, and means on said sleeve portion disposed above said flange for temporarily supporting and for angularly positioning the electric lamp within its socket, said means comprising a lug having a portion providing a vertical lamp positioning surface extending parallel to the axis of said sleeve and another portion providing a lamp supporting surface facing said positioning flange.

6. A prefocusing collar for attachment to the base of an electric lamp comprising a flat positioning flange provided at its inner periphery with a sleeve portion, and a lug extending upwardly from the outer periphery of said flange and provided at its lower extremity with a notch in one of its radial sides.

7. In combination, an electric lamp socket com-

prising a positioning ring which is slotted at its inner periphery, and an electric lamp for insertion in said socket comprising a base adapted to be inserted into said positioning ring from the bottom, said base having laterally projecting flange means for engagement with the bottom of said positioning ring, and engagement means on said base at the upper side of said flange means adapted to pass through the slotted portion of said ring and to permit rotation of said base relative to said ring, said engagement means having a portion arranged to engage the upper surface of said ring, upon rotation of said base, to thereby temporarily support the lamp within the socket and another portion arranged to engage a side wall of the slotted portion of the ring to thereby position the lamp angularly within the socket.

FRANK E. CARLSON.
